UNITED STATES PATENT OFFICE.

SAMUEL H. ARRELL, OF GUTHRIE, OKLAHOMA TERRITORY.

DESIGN FOR A TOBACCO-CASE.

SPECIFICATION forming part of Design No. 25,610, dated June 9, 1896.

Application filed April 14, 1896. Serial No. 587,564. Term of patent 7 years.

To all whom it may concern:

Be it known that I, SAMUEL H. ARRELL, a citizen of the United States, residing at Guthrie, in the county of Logan and Territory of Oklahoma, have invented a new and original Design for Tobacco-Cases, of which the following is a specification.

The invention relates to a new and original design for tobacco-cases.

- 10 The object of the present invention is to provide an ornamental and attractive case which will enable tobacco to be displayed in an ornamental manner, and the essential feature resides in a case provided with a rectangular series of square compartments, the compartments having the appearance of being arranged in oppositely-inclined parallel rows, the middle rows being extended at the bottom of the rectangular figure.
- 20 The figure of the drawing is a perspective view of a tobacco-case, showing my new and original design.

Referring to the drawing, 1 designates a series of square compartments arranged in the form of a rectangular figure with its diagonals disposed vertically and horizontally,

and the sides of the rectangular series of compartments form oppositely-disposed V-shaped figures.

The square compartments are arranged in 30 parallel inclined rows 2, and the middle rows are provided with lower extensions 3, and the bottom of the entire set of square compartments form a continuous zigzag or duplicated V-shaped figure 4. The V-shaped figures 6 35 are formed at the sides of the series of compartments.

It will be seen that the case presents an ornamental appearance and will enable its contents to be arranged in an attractive manner.

What I claim is—

The design for display-cases, herein shown and described.

In testimony that I claim the foregoing as 45 my own I have hereto affixed my signature in the presence of two witnesses.

SAMUEL H. ARRELL.
